CAMPER TOP

William A. Ritter and Edward J. Anderson, both of 585 4th St., San Fernando, Calif. 91340

Filed Mar. 23, 1966, Ser. No. 1,602

Term of patent 14 years

(Cl. D14—27)

FIG. 1

FIG. 2

FIG. 3

FIG. 4

FIG. 5

We claim:

The ornamental design for a camper top, substantially as shown and described.
